UNITED STATES PATENT OFFICE

92,442

DESIGN FOR A TELEPHONE INSTRUMENT OR THE LIKE

Everett Worthington, Chicago, Ill., assignor to
The Stromberg-Carlson Telephone Manufacturing Company, Rochester, N. Y., a corporation of New York

Application April 6, 1934, Serial No. 51,326

Term of patent 14 years

To all whom it may concern:

Be it known that I, EVERETT WORTHINGTON, a citizen of the United States, residing at Chicago, in the county of Cook and State of Illinois, have invented a new, original, and ornamental Design for Telephone Instruments or the like, of which the following is a specification, reference being had to the accompanying drawing, forming part thereof,

Fig. 1 is a front perspective view of the complete instrument; Fig. 2 is a perspective view of the base of the instrument viewing it from a point above and to the front thereof; and Fig. 3 is a top view of a fragment of the hand telephone.

I claim:

The ornamental design for a telephone instrument or the like, as shown.

EVERETT WORTHINGTON.
